UNITED STATES PATENT OFFICE.

WILLIARD WOOD, OF SAN FRANCISCO, CALIFORNIA.

ATTACHMENT FOR TELEPHONE INSTRUMENTS.

1,078,117.

Specification of Letters Patent. Patented Nov. 11, 1913.

Application filed July 3, 1912. Serial No. 707,622.

To all whom it may concern:

Be it known that I, WILLIARD Wood, a citizen of the United States, residing at San Francisco, in the county of San Francisco and State of California, have invented certain new and useful Improvements in Attachments for Telephone Instruments, of which the following is a specification.

This invention relates to improvements in telephone attachments, and particularly to means for conveniently attaching a cabinet for containing a memorandum pad and pencil to the ordinary desk telephone.

The object of the invention is to provide means for securing a pad and pencil to a telephone instrument which is readily accessible to the user but is put out of sight when not in use.

Another object of the invention is to provide a simple and inexpensive cabinet which can be readily secured to and beneath the base of an ordinary telephone stand, without marring the looks of the stand.

Another object of the invention is to provide a cabinet provided with a drawer containing a pad and pencil, which can be readily attached to telephones now in use without causing any change whatever to be made in said instruments.

Another object of the invention is to provide means for attaching a pad and pencil to a telephone instrument, which does not leave any unsightly projections protruding from the instrument to mar its looks or cause it to be accidentally knocked over.

In carrying out my invention I provide a cylindrical cabinet containing a drawer, said drawer serving to hold a memorandum pad and pencil for use by any person having need of the same when using a telephone instrument and secure said cabinet to the base of the telephone instrument, without changing the instrument in any manner or even having to tap screws into the same. By opening the drawer of the cabinet the pad and pencil immediately become accessible to the user and in the most convenient place, when the operator is finished he closes the drawer and the pad and pencil are out of sight beneath the base of the telephone instrument.

The details of construction are clearly set forth in the accompanying drawings forming a part of this specification.

In the drawings, Figure 1 is an elevation of a telephone instrument with my improved

cabinet attached thereto. Fig. 2 is a section through the cabinet showing the base of the instrument in elevation. Fig. 3 is a horizontal section on line 3-3 of Fig. 1, showing the drawer of the cabinet open. Fig. 4 is a plan view of my improved cabinet, and Fig. 5 is a detail sectional view, showing a spring finger in engagement with the retaining ring.

Like numerals of reference indicate corresponding parts in the several figures of the drawings.

The telephone instrument is indicated by the numeral 1 and its base designated at 2. A collar 3 is slipped over the base shaped to conform to the upper surface of said base, said collar being provided with a plurality of bayonet slots 4 to coöperate with lugs 5 secured to upstanding resilient fingers 6, said fingers being rigidly attached to a cabinet 7. The cabinet 7 is made of sheet metal or any suitable material, and is so constructed as to conform to the shape and size of the base of an ordinary desk telephone. Said cabinet is open at the top but is provided with a bottom 8. Secured within the cabinet are a number of posts 9, which extend from the bottom to the top of the same and serving as supports for the telephone instrument. The cabinet is provided with a drawer 10, the front of said drawer being made to follow the contour of the outside of the cabinet and is provided with a knob 11. A memorandum pad 12 is placed within the drawer and rests against stops 13 secured to the bottom of the drawer. A pencil holder 14 is also secured within said drawer to support a pencil for the user of the telephone instrument.

While I have shown my improved cabinet as cylindrical and plan view, it is to be understood that I do not desire to limit myself to a cylindrical cabinet, but believe any shape that can be attached to the base of a telephone instrument, will come within the spirit and scope of my invention.

In practice the operation of my invention is as follows: The ring 3 is slipped over the telephone instrument and the cabinet is placed against the bottom of the instrument and secured to said ring through the medium of the bayonet slots 4, lugs 5 and fingers 6, said means securely holding the cabinet and ring together and at the same time rigidly attaching the cabinet to the base of the telephone instrument. By reference to Fig. 1

of the drawings it will be seen that my improved attachment does not mar the looks of the instrument at all but merely raises the height of said instrument a short distance.

5 By again referring to the same figure it will be seen that no attachments protrude from the instrument causing it to look unsightly or be in the way of a user.

When a person using a telephone desires a 10 pad and pencil all that it is necessary for them to do is to pull out the drawer and the pad and pencil is at hand. The operator when finished can tear the top leaf off the pad and then close the drawer when the 15 pad and pencil are shut in from view, and the operator has his memoranda with him.

I do not desire to limit myself to the exact construction shown in the drawings, but believe those skilled in the art can make many 20 modifications in the details of construction without departing from the spirit of my invention.

Having thus described my invention what I claim is,

25 1. An attachment for desk telephone instruments comprising a cabinet, said cabinet containing a drawer provided with a pad and pencil, a ring adapted to fit over the base of a telephone instrument, and means 30 for securing said cabinet to the ring and to the instrument.

35 2. An attachment for desk telephone instruments comprising a circular cabinet containing a drawer, said cabinet being provided with upstanding resilient fingers having lugs secured thereto, and a plate provided with slots for engaging said lugs, for the purpose of securing the cabinet to the instrument.

40 3. As an article of manufacture, an attachment for telephones comprising a band

which conforms in shape with the exterior of the lower portion of the base of a telephone, a circular cabinet having an open top, means which project above the upper edge of the 45 cabinet to engage with the band, and a drawer associated with the cabinet.

4. In a device of the character set forth, a band which is adapted to be placed over the base of a telephone, a circular cabinet having 50 means for engagement with the band to associate the cabinet with the telephone and with upward projecting studs attached to the cabinet to engage the bottom of the base of the telephone, and a drawer maintained 55 in movable engagement with the cabinet.

5. A supplemental base for telephones comprising a circular cabinet having upward projecting fingers, a band which is adapted to encircle the lower portion of the base of 60 the telephone and with which the fingers engage to hold the parts associated with the telephone, and a drawer associated with the cabinet.

6. In a device of the character set forth, a 65 container having a bottom, a side wall and a drawer maintained in slidale engagement with the bottom said drawer having a curved front which corresponds with the contour of the side wall, means attached to the 70 cabinet which extend above the upper edge of the side wall thereof, and means associated with the base of an instrument for associating the cabinet with the instrument to provide a supplemental base and a receptacle 75 for articles.

In testimony whereof I affix my signature in presence of two witnesses.

WILLIARD WOOD.
